(57) **CLAIM**

The ornamental design for an air compression apparatus, as shown and described.

DESCRIPTION

FIG. 1 is a front, perspective view of an air compression apparatus;

FIG. 2 is a front view thereof;

FIG. 3 is a top view thereof;

FIG. 4 is a right-side view thereof; the left-side view thereof (not included) being a mirror image thereof;

FIG. 5 is a rear view thereof;

FIG. 6 is a bottom view thereof;

FIG. 7 is a rear, perspective view thereof; and,

FIG. 8 is a cross-sectional view taken along line 8-8 in FIG. 3.

The broken lines depict unclaimed portions of the air compression apparatus and form no part of the claimed design.
